UNITED STATES PATENT OFFICE.

OMER J. RAINVILLE, OF PAWTUCKET, RHODE ISLAND.

DESIGN FOR A BOTTLE-CAP REMOVER.

45,171.

Specification for Design.

Patented Jan. 20, 1914.

Application filed November 19, 1913. Serial No. 802,000. Term of patent 7 years.

To all whom it may concern:

Be it known that I, OMER J. RAINVILLE, a citizen of the United States, residing at Pawtucket, in the county of Providence and State of Rhode Island, have invented a new, original, and ornamental Design for a Bottle-Cap Remover, of which the following is a specification, reference being had to the accompanying drawing, in which the figure represents a side view of the bottle-cap remover, showing my design.

I claim—

The ornamental design for a bottle-cap remover, as shown.

OMER J. RAINVILLE.

Witnesses:

ADA E. HAGERTY,
J. A. MILLER.
